UNITED STATES PATENT OFFICE.

EDGAR F. HATHAWAY, OF DORCHESTER, MASSACHUSETTS, ASSIGNOR, BY MESNE ASSIGNMENTS, TO BARBER-COLMAN COMPANY, OF ROCKFORD, ILLINOIS, A CORPORATION OF ILLINOIS.

WARP-LEASING MACHINE.

Application filed January 13, 1919. Serial No. 270,893.

To all whom it may concern:

Be it known that I, EDGAR F. HATHAWAY, a citizen of the United States, and a resident of Dorchester, in the county of Suffolk and 5 Commonwealth of Massachusetts, have invented Improvements in Warp-Leasing Machines, of which the following description, in connection with the accompanying drawings, is a specification, like characters on 10 the drawings representing like parts.

This invention relates to warp leasing machines, being more particularly intended to provide an efficient but simple and rapidly working mechanism for placing the threads 15 of a warp in leased arrangement. The invention will be best understood by reference to the following description when taken in connection with the accompanying illustration of one specific embodiment thereof, 20 while its scope will be more particularly pointed out in the appended claims.

In the drawings:—

Figure 1 is a front elevation in partial section and partly broken away, showing the 25 principal working parts of a warp leasing machine embodying one form of the invention.

Fig. 2 is an end elevation looking from the left in Fig. 1, showing the warp leasing machine illustrated therein;

Fig. 3 is a plan view of the warp leasing machine shown in Fig. 1;

Fig. 4 is a plan view, on an enlarged scale, showing one end of the travelling carriage and the thread-separating mechanism;

Fig. 5 is an end elevation, in partial section, of the parts shown in Fig. 4;

Fig. 6 is a sectional detail showing the 40 clutch for the separating worm in disconnected relation;

Fig. 7 is a perspective showing the action of the two leasing members on the warp threads; and

Fig. 8 is a sectional detail showing the carriers for the leasing cords attached to the lease rods in place of the helical leasing members.

Referring to the drawings and to the 50 embodiment of the invention therein shown, the machine there disclosed (see Fig. 1) comprises a supporting frame having supporting legs 10 which carry the bed 11 and the upright end frame supports 12. The

frame members 12 are connected at the rear 55 by a tie rod 13, and at the front by a similar rod 14.

In the illustrated form of machine the sheet of warp threads is held suitably stretched with the threads substantially parallel and 60 preferably, as herein shown, they are acted upon progressively by suitable thread-separating mechanism to facilitate the action of the leasing elements proper and thereafter by suitable leasing elements which advance with relation to the stretched and 65 separated threads and have provision whereby the threads are so positioned with relation to the leasing members that successive threads will be disposed in opposite arrangement above and below the two members and with the line of thread crossings between the 70 two.

Any common or suitable thread-separating mechanism may be employed. The form 75 shown herein comprises a helically grooved sleeve 15 adapted to slide along the tie rod 14 and to advance slowly with relation to the threads, the threaded sleeve or worm serving to smooth out the foremost threads, 80 separate them and spread them apart, as indicated in Fig. 7, so that they may be readily operated upon by the leasing members. The latter may have any desired shape and may be given any desired movement, but herein 85 a highly effective leasing action is secured by providing leasing members in the form of rods 16 and 17 having end portions 18 and 19 which enter between the separated warp threads and arrange them in leased position 90 on the rods by hooking successively under and over a thread or threads, thus positioning regularly recurrent threads of the set over or under the leasing rod. To effect this action I preferably provide means for 95 rotating the ends of the rods 16 and 17 and direct these ends helically. Conveniently they may form a complete helix of one or more turns or spires, forming an open screw which as the rod rotates will screw its way through the series of warp threads. In 100 this action the sheet of threads is not essentially displaced and no strain is placed upon the threads, but the helical ends 18 and 19 pass through the spaces between the 105 threads alternately from above and below, and the threads pass through the open-centered coil until they are delivered with-

out substantial displacement to the upper or lower side of the lease rod, as the case may be.

Preferably though not necessarily, one helix is left handed and the other right handed and the two rods are rotated in opposite directions. Thus, the helix 18 is right handed and its rod is rotated clockwise while the helix 19 is left handed and 10 its rod is rotated counterclockwise.

Referring first to the devices for holding and controlling the warp threads, the latter have their ends fastened to the thread clamp 20 (see Figs. 1, 2 and 3) which may be of 15 any desired construction. When the machine is to be loaded, the warp beam may be positioned back of the machine, being brought there, for example, on a truck. The ends of the warp threads are then clamped 20 by the clamp 20 and the latter is carried up and over the machine, and over the tie rod 14 at the front end of the machine, leading the sheet of warp threads over one member 21 of the back clamp. The sheet of warp 25 threads is then clamped at the back of the machine in the back clamp by applying the remaining member 22 of the clamp, the latter being of any suitable construction, but preferably provided with some form of 30 clamping lever, such as the cam levers 23, by means of which the threads are clamped tightly between the clamp members 21 and 22. The sheet of warp threads is then stretched tightly across the top of the machine. This may be accomplished by relying 35 simply on the weight of the depending front clamp 20, the latter being allowed to hang loosely in place, or the latter may be yieldably drawn down to stretch the 40 threads, as by removably securing it to the spring-pressed supports 24. The latter are secured to the upright rods 25 which, in turn, are fastened to the cross rod 26 secured to the machine frame 10. The supports 24 are pressed yieldably downward by 45 the coiled springs 27 which encircle the rods 25.

Referring now to the thread-separating and leasing devices, in order to permit 50 progressive action of the latter across the warp, the thread-separating worm 15 and the leasing members 16 and 17 are mounted upon a travelling carriage, although, if desired, these devices might work in a fixed 55 position and the warp support be made to travel. The travelling carriage may be of any suitable construction, but herein comprises a carriage bed 30 adapted to slide upon guideways 31 on the machine bed 11 60 and carrying the bar 32 sufficiently prolonged to serve as a support for the leasing rods and their actuating or driving devices. The bar may be guided and supported by one or more roller supports 33 on the machine frame, and additional roller 65

supports 34 carried by standards detached from the machine frame may be availed of for the overhanging end of the carriage bar. During the leasing operation, the leasing carriage is given a feeding movement 70 from left to right, as viewed in Fig. 1. Any suitable mechanism may be employed for imparting this feeding movement, but herein there is shown a lead screw 35 adapted to engage the nut 36 carried by the carriage 75 and impart to the latter a movement of traverse. To permit the operator to move the carriage quickly from one part of the bed to another, the nut is split and the two sections connected to the segmental gears 80 37 and 38 (see Figs. 4 and 5), the gear 38 being connected with a handle 39. The latter has a spring-pressed pin 40 adapted to engage an opening in the bracket 41 on the carriage bed, being thereby locked in 85 its lowermost or carriage feeding position. The pin has a hooked end 42 (Fig. 3) by which it may be unlocked and the lever lifted, the pin snapping back over the top of the bracket 41 so as to hold the lever 90 elevated or in its non-feeding position during such periods as a rapid adjustment of the carriage is required.

The lead screw 35 may be driven in any desired manner, but herein the same is given 95 an intermittent feeding movement from the main driving shaft 45, the extent of which movement may be adjusted by finely graduated amounts. This is herein accomplished by means substantially the same as disclosed 100 in prior patent to Lea, No. 1,090,401, dated March 17, 1914. This is best shown in Fig. 2 and, briefly, consists of a double rack 46 adjustably and eccentrically connected to the crank disc 47 and engaging with the 105 gears 48 and 49 which effect a step-by-step driving movement of the lead screw 35 by means of a ratchet and pawl connection. The crank disc 47 is driven from the drive 110 shaft 45 by means of the intermeshing gears 50 and 51, the latter on the drive shaft 45.

To impart movement to the leasing members and the separating devices on the travelling carriage, the latter (see Fig. 1) is provided with the pinion 52 which is held 115 within the depending support 53 on the carriage and has a splined driving connection to the drive shaft 45. The pinion 52 meshes with the gear 54 on the carriage, the latter being mounted on the countershaft 55. Connected to be driven by the countershaft, is the spiral gear 56 which drives the short, inclined shaft 57 by means of the intermeshing spiral gear 58. To impart a rotative movement to the thread-separating worm 15, the shaft 57 has secured thereto the collar 60, (Figs. 5 and 6) which latter is normally clutched to the sleeve 61 carrying at its end the bevelled pinion 62 meshing with the bevelled gear 63 threaded or otherwise secured 125 130

to the end of the worm sleeve. The worm sleeve is advanced along the rod 14 and its intermeshing relation to the drive sleeve 61 preserved by means of the yoke piece 64 fastened to the bearing 65 for the drive sleeve and engaging a necked-down or grooved portion of the worm sleeve. In the normal operation of the machine, as the carriage is advanced intermittently, step by step, the drive shaft 57 is constantly rotated, imparting a constant and uniform rotation to the separating worm sleeve 15. Preferably, however, there is provided means for disconnecting the latter at will and turning it either backward or forward to correct errors in separation or to make any desired end adjustment which may be required. For this purpose (see Figs. 5 and 6) the drive sleeve 61 carries the collar 66 non-rotatably secured on the sleeve 61 but capable of sliding movement thereon. The collar 66 has secured thereto the hand wheel 67 by means of which it may be moved lengthwise the shaft 57 or rotated on the shaft. The collar 66 is also provided with the pin 88 which normally seats in an opening in the drive collar 60 and serves to connect the drive sleeve 61 with the shaft 57 for rotative movement. When desired, however, the hand wheel may be lifted to disengage the pin from the collar, disconnecting the drive sleeve and drive shaft, and may also be turned either right-handedly or left-handedly to turn the thread-separating worm forward or backward as may be required. When the hand wheel is released, the pin will snap back into engagement with the collar, under the pressure of the expansion spring 66^a, thus restoring the driving connection.

The advancing end of the thread-separating worm is preferably given a formation such as the fluted, tapered form illustrated, so that the threads which are first engaged by the advancing sleeve are smoothed out and placed under an increasing tension. As they advance up the sleeve, they are engaged by the thin, wedge-shaped lip 70 (Fig. 4) of the worm and the threads are picked off one by one, passing into the end of the groove 71, the pitch of which rapidly increases. The series of threads engaged by the worm are thus spread apart as indicated in Fig. 7. The separated threads, after being leased, pass off from the worm into a stationary shield or apron 72 (see Figs. 4 and 5) which is fitted into a groove in the back end of the worm and which prevents contact between the threads and the connections between the worm and the driving shaft 57. The threads are delivered by this apron again to the stationary rod 14 as the worm advances with the leasing carriage.

Referring now to Fig. 3, the leasing members 16 and 17 are secured to the rotary rods

80 and 81 which are supported near their forward ends by the rollers 82 carried on the bracket 83 fastened to the bar 32. At their opposite ends they are removably and detachably secured to the driving sleeves 70 or sockets 84 which may be similar in construction to the sockets 8 shown in Patent No. 980,086, to Field et al. The driving sockets 84 are rotatably mounted in the upright bracket 85 carried near the end of the bar 32, and are rotated preferably with a continuous rotary motion and at a uniform rate, but in opposite directions, by means of the intermeshing gears 86 and 87. The gear 87 (see Fig. 2) is driven by the pinion 88 mounted on the shaft 89, the latter in turn being driven by the driving shaft 90 having at one end the universal joint connection 91 to the shaft 89, and at the opposite end the universal joint connection 92 to the counter-shaft 55 on the carriage 30.

By the described mechanism, as the carriage 30 is advanced step by step, the continuous rotary movement of the warp-separating worm 15 separates and opens up the sheet of warp threads, while the concomitant continuous rotation of the lease rods 80 and 81 causes the helices to screw their way through the warp threads, disposing them along the lease rods, as shown at the left in Fig. 7, as the rods advance across the warp the leased threads passing between the lease rods and the rollers 82. This action which, since the principal parts have a continuous uni-directional rotary movement, may be carried on at a high rate of speed is continued until the entire warp has been placed in leased relation to the two rods 80 and 81. When this condition is reached, the lease rods may be withdrawn from the warp and lease cords substituted therefor. To facilitate this operation, the helical ends of the lease rods 16 and 17 (Fig. 7) are detachably secured thereto, as by the threaded connections 93 and 94. After the warp is leased, these ends which then protrude beyond the edge of the warp are disconnected from the rods and are replaced by the threaded couplings 95 and 96, as shown in Fig. 8, such couplings having secured thereto the lease cords 97 and 98. The opposite ends of the rods are then disconnected from the driving sockets 84 and the lease cords 97 and 98 drawn through the warps, leaving the lease cords in leased relation to the sheet of warp threads. The ends of the lease cords being disconnected from the couplings 95 and 96, the warp may be then removed from the machine, the latter loaded with a fresh warp and the operation repeated.

In order to maintain the desired angular relation between the warp threads and the separating worm, and to compensate for any irregularities in the spacing of the threads, the warp may be given a compensating ad-

justment by means such, for example, as those in the aforesaid patent of Field et al, No. 980,086, and patent to Field and Hathaway, No. 871,681, and herein best shown in Fig. 1. For this purpose the hand rod 100 is provided, the turning of which moves the sprocket chain 103 through the intermeshing gears 101 and 102, and turns the worm wheel 104. The worm wheel engages with rack teeth 105 formed on the clamp member 21, the latter being loosely mounted in the frame of the machine. Such movement of the worm wheel imparts a longitudinal sliding movement to the clamp, serves to shift the warp longitudinally of the machine and varies the angular relation of the threads to the separating mechanism.

The machine is also preferably provided with means whereby the operator can stop and start the same instantly, giving opportunity for making the necessary manual corrections in the separation of the threads. Herein such means are shown in Fig. 1 as similar to those illustrated in Patent No. 1,190,761, to Hathaway. For this purpose the hand rod 100 is capable of a sliding movement, as well as a rotary movement, and has one end secured to the lever 110, the lower end of which operates simultaneously a brake member 111 on the brake 112, and a clutch member 113, which latter is adapted to connect the main driving shaft 45 to, or disconnect the same from, the main driving pulley 114. Movement of the hand rod longitudinally in one direction serves to disconnect the power from the machine and apply the brake, while movement in the opposite direction releases the brake and connects the driving power to the machine, the two positions of the lever 110 being indicated in dotted lines. As described in the aforesaid Patent No. 1,190,761, the hand rod 100 is also capable of being rocked along the curved guide 115 into the dotted line position shown in Fig. 2, by means of the swinging supporting arms 116, so that it may be thrown up out of the way when the machine is being loaded or unloaded.

I have described in detail the various elements disclosed in the particular embodiment of my invention chosen for purposes of illustration, and in doing so have referred to the various parts by the specific names, but with an identifying or descriptive rather than a definitive purpose. The principles exemplified by the particular example shown and described which I claim as new and desire to secure by Letters Patent I shall express in the following claims:—

1. A leasing machine having, in combination, a framework comprising a bed, a rod extending longitudinally of and above the bed and along one side thereof, means at the other side of the bed and above the bed for supporting a warp clamp, means at the

first-mentioned side of the bed and below the bed to receive a warp clamp, the warp extending from the first-mentioned clamp to said rod and thence downwardly to the second-mentioned clamp, a carriage mounted on the bed to travel below the sheet of threads, a thread-spacer mounted on said carriage and slidable on said rod into engagement with the threads extending over said rod, and leasing means located on said carriage between said spacer and the first-mentioned clamp.

2. A leasing machine having, in combination, a bed, a warp-supporting rod extending longitudinally of the bed, means cooperating with said rod to support a sheet of threads over the bed, a carriage mounted on the bed to travel below the sheet of threads, a thread-spacing device mounted on said carriage and slidable upon said rod into engagement with the threads extending over the rod, two lease rods moving with the carriage substantially in the plane of the warp, each of said lease rods having at its forward end a removable section provided with an open helix, and means for rotating said lease rods in opposite directions, said lease rods being detachably secured to the rotating means.

3. A leasing machine having, in combination, a bed, a warp-supporting rod extending longitudinally of the bed, means cooperating with said rod to support a sheet of threads over the bed, a carriage mounted on the bed to travel below the sheet of threads, a thread-spacing device mounted on said carriage and slidable upon said rod into engagement with the threads extending over the rod, two lease rods moving with the carriage, each of said lease rods having an open helix at its forward end, and means for rotating said lease rods.

4. A leasing machine having, in combination, two spaced supports between which a sheet of warp threads extends, operating mechanism, and means for causing relative traveling movement between said warp supports and said mechanism, said mechanism comprising a thread spacer mounted on one of said supports, two lease rods located between said spacer and the other support, each of said rods having at its forward end a removable section provided with an open helix, said rods lying substantially in the plane of the warp, and means for rotating said rods in opposite directions, said rods being detachably secured to the rotating means.

5. A leasing machine having, in combination, two spaced supports between which a sheet of warp threads extends, operating mechanism, and means for causing relative traveling movement between said warp supports and said mechanism, said mechanism comprising a thread spacer, two lease rods

- located between said spacer and one of said warp supports, each of said rods having at its forward end a removable section provided with an open helix, and means for 5 rotating said rods, said rods being detachably secured to the rotating means.
6. A leasing machine having, in combination, two spaced supports between which a sheet of warp threads extends, operating 10 mechanism, and means for causing relative traveling movement between said warp supports and said mechanism, said mechanism comprising a thread spacer mounted on one of said supports, two lease rods located between said spacer and the other support, each of said rods having an open helix at its forward end, and means for rotating said rods in opposite directions, said rods being detachably secured to the rotating means.
- 15 7. A leasing machine having, in combination, two spaced supports between which a sheet of warp threads extends, operating mechanism, and means for causing relative traveling movement between said warp supports and said mechanism, said mechanism comprising a thread spacer mounted on one of said supports, two lease rods located between said spacer and the other support, each of said rods having an open helix at its forward end, and means for rotating said rods.
- 20 8. A leasing machine having, in combination, two spaced supports between which a sheet of warp threads extends, operating mechanism, and means for causing relative traveling movement between said warp supports and said mechanism, said mechanism comprising a thread spacer mounted on one of said supports, two lease rods located between said spacer and the other support, each of said rods having an open helix at its forward end, and means for rotating said rods.
- 25 9. A warp-leasing machine having, in combination, a main frame comprising a bed, means on the main frame for supporting a warp clamp above and at the rear side of the bed, a rod supported in the main frame above and at the forward side of the bed and parallel with said clamp, means on the frame below said rod for supporting a second warp clamp, the threads extending from the first mentioned clamp to said rod and thence downwardly to the second clamp, a carriage mounted to travel along the bed below the sheet of threads supported by said rod and the first mentioned clamp, mechanism on said carriage for selecting and spacing the threads and for leasing the spaced threads, a drive shaft extending longitudinally of and carried by the main frame, a drive pulley mounted on said shaft at one end of the main frame, a clutch member on the drive shaft for connecting the pulley to the shaft, a brake on said shaft adjacent to the clutch member, means for connecting the drive shaft to the mechanism on the carriage, a lead screw extending longitudinally of and mounted in the main frame, a nut connected to the carriage and engaging said lead screw, means at the end of the main frame opposite to the drive pulley for connecting the lead screw to the drive shaft, 70 mechanism for longitudinally shifting the first mentioned warp clamp, and a hand rod extending longitudinally of the main frame and above the threads and connected to operate said clamp-shifting means, the clutch 75 and the brake.
- 10 10. A textile machine having, in combination, a framework comprising a bed, a rod extending longitudinally of and above the bed and along one side thereof, means at the other side of the bed and above the bed for supporting a warp clamp, means at the first-mentioned side of the bed and below the rod to receive a warp clamp, the warp extending from the first-mentioned clamp to said rod 80 and thence downwardly to the second-mentioned clamp, a carriage mounted on the bed to travel below the sheet of threads, and a thread spacer mounted on said carriage and 85 slideable on said rod into engagement with the threads extending over said rod.
- 11 11. A textile machine having, in combination, a framework comprising a bed, a rod extending longitudinally of and above the bed and along one side thereof, means at the other side of the bed and above the bed for supporting a warp clamp, the warp extending from the clamp to said rod, a carriage mounted on the bed to travel below the sheet of threads, a thread-spacer mounted 90 on said carriage for engagement with the threads, and means for adjusting said clamp to maintain the desired angular relation between the threads and the spacer.
- 12 12. A warp-leasing machine having, in combination, a carriage, a supporting rod extending rearwardly from the carriage, a bracket extending upwardly from the rear portion of said rod, two driving sockets rotatably mounted in said bracket, intermeshing gears connected to said sockets, means for driving said gears, lease rods having their rear ends removably mounted in said sockets, each of said rods having at its forward end a removable section provided with an open helix, and means on the forward portion of said supporting rod for supporting the lease rods.
- 13 13. A leasing machine having, in combination, two lease rods, each of said rods having at its forward end a removable section provided with an open helix, and means for rotating said rods, said rods being detachably connected to the rotating means.
- 14 14. A warp-leasing machine having, in combination, a main frame, means on the main frame for supporting a warp, a carriage, means to cause the carriage to travel longitudinally of the frame and transversely of the warp threads, means on the carriage 130

for selecting and spacing successive threads, a member extending rearwardly from the carriage, a bracket on the rear portion of said member, lease-rod holders rotatably mounted on said bracket, lease rods having their rear ends removably connected to said holders, each of said rods having an open helix at its forward end to engage spaced threads, and means for causing relative adjusting movement between the warp and the selecting means.

15. In a warp-leasing machine, in combination, a carriage, means on said carriage for supporting a thread selector, a member extending rearwardly from the carriage, a bracket on the rear portion of said member, lease rods having their rear ends removably connected to said bracket, the forward ends of said rods being adjacent to the thread selector, and means near the forward portion of said member for supporting the lease rods.

16. In a warp-leasing machine, in combination, a carriage, a supporting rod extending rearwardly from the carriage, a bracket on the rear portion of said rod, lease-rod holders rotatably mounted on said bracket, lease rods having their rear ends removably connected to said holders, means near the forward portion of said supporting rod for supporting the lease rods, and means for rotating said holders.

17. In a warp-leasing machine, in combination, a carriage, a supporting rod extending rearwardly from the carriage, a bracket on the rear portion of said rod, lease rods having their rear ends removably connected to said bracket, and means near the forward portion of said supporting rod for supporting the lease rods.

18. A warp-leasing machine having, in combination, a main frame, means on the main frame for supporting a warp, a carriage, means to cause the carriage to travel longitudinally of the frame and transversely of the warp threads, means on the carriage for selecting and spacing successive threads, rotatable lease-rod holders mounted to travel with said carriage, lease rods having their rear ends removably connected to said holders, each of said rods having an open helix at its forward end to engage spaced threads, and means for causing relative adjusting

movement between the warp and the selecting means.

19. A textile machine having, in combination, a framework comprising a bed, a rod extending longitudinally of and above the bed and along one side thereof, means at the other side of the bed and above the bed for supporting a warp clamp, the warp extending from the clamp to said rod, a carriage mounted on the bed to travel below the sheet of threads, a thread spacer mounted on said carriage and slideable on said rod into engagement with the threads extending over said rod, and means for adjusting said clamp to maintain the desired angular relation between the threads and the spacer.

20. A textile machine having, in combination, a framework comprising a bed, a rod extending longitudinally of and above the bed and along one side thereof, means at the other side of the bed and above the bed for supporting a warp clamp, means at the first-mentioned side of the bed and below the bed to receive a warp clamp, the warp extending from the first-mentioned clamp to said rod and thence downwardly to the second-mentioned clamp, and means tending to move said clamp-receiving means to tension the warp.

21. A textile machine having, in combination, a bed, a warp-supporting rod extending longitudinally of the bed at one side thereof, means at the other side of the bed to cooperate with said rod in supporting a sheet of threads over the bed, a carriage mounted on the bed to travel below the sheet of threads, and a thread-selecting worm mounted on said carriage and slideable upon said rod into engagement with the threads extending over the rod.

22. A textile machine having, in combination, a bed, a warp-supporting rod extending longitudinally of the bed at one side thereof, means at the other side of the bed to support a warp clamp, a carriage mounted on the bed to travel below a sheet of threads extending between said clamp and rod, and means moving with said carriage to operate upon the threads adjacent to the rod.

In testimony whereof, I have signed my name to this specification.

EDGAR F. HATHAWAY.
